DESIGN.

O. HEINIGKE.

CARPET.

No. 18,392.

Patented June 19, 1888.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 18,392, dated June 19, 1888.

Application filed January 26, 1888. Serial No. 262,024. Term of patent 3½ years.

To all whom it may concern:

Be it known that I, OTTO HEINIGKE, of New Utrecht, Long Island, New York, have invented a new and original Design for Carpets, of which 5 the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

The main feature of my design is the figure A, which is closely repeated over the face of the carpet in an unbroken succession.

The figure A is a circular flower form hav-

ing a center composed of small block-work, and having around the center concentric circles of small leaves which are oval or oblong in general character. These small flower-leaves form a sort of leaf net-work covering the entire surface of the carpet between the flower centers. Each alternate flower form is made 25 prominent in the design, while those between are less conspicuous.

What I claim as new, and desire to secure by Letters Patent, is—

The design for carpets, consisting of the design substantially as shown.

OTTO HEINIGKE.
